RAKE DRIVING MECHANISM FOR
SEDIMENTATION TANKS

Charles H. Scott, Westport, Conn., assignor to
The Dorr Company, New York, N. Y., a corpora-
tion of Delaware

Application April 25, 1940, Serial No. 331,513

6 Claims. (Cl. 74—225)

This invention relates to mechanically cleaned sedimentation tanks, and more specifically to rope-driven sediment collecting mechanism therefor.

The rope-driven sludge collecting means herein contemplated is of the reciprocating type, being moved back and forth in the tank, to convey the settled matter or sludge to a point of outlet.

The invention furthermore particularized relates to improvements in the construction and arrangement of the driving means for the rope that actuates the sludge collecting means.

The problem in the operation of such a rope drive differs from other rope driven apparatus, for instance hoists, and rope drive systems that are substantially vertical, and in which the weight of a load lifted and of certain counter weights tend to take up or absorb automatically and at all times any potential slack in the rope. Under conditions where thus the rope is automatically sufficiently tensioned to prevent an undesirable slack condition thereof, there is normally no danger of the rope windings on the rope winding drums becoming slack and entangled and fouled as a result of slackness. Consequently, under those conditions, the rope is not likely to get jammed and finally broken due to such entanglements.

By way of contrast, it should be understood that a problem arises where an endless rope drive operates in a generally horizontal plane as in the case where it actuates a reciprocal sludge collecting device in a horizontally extending sedimentation tank. Under such conditions the rope may develop a slack which, if unnoticed or neglected, may lead to disarrangement of the rope windings on the rope winding drums, and unless special provisions are made or precautions taken, such as contemplated by this invention, the rope may become fouled, jammed, and finally broken.

It is one object of this invention to provide an improved rope driving mechanism in which such potential trouble is minimized or precluded.

These objects are obtained largely by constructing and arranging the rope driving mechanism in such a manner that when rope slackness develops, a winding or windings of the rope, rather than becoming entangled or jammed in the drive mechanism and doing damage, will simply be allowed to slip off the rope winding drum or drums, and thereby to render the rope idle rather than permitting it and the mechanism to get damaged.

To this end, a form of an improved mechanism proposed by this invention has a pair of rope

winding drums disposed side by side, to rotate about vertical axes, and so arranged with respect to the body of the mechanism, that the rope winding drums are disposed underneath the drive elements therefor, and so as to be substantially free from encumbrances from below, namely to the extent that rope windings when slack may detach themselves from the drum to prevent damage by entanglement. By the same token, the rope windings may be readily reapplied to the winding drums substantially without the need of dismantling the mechanism.

Other objects of the invention are to provide a drive unit for the rope, which is simple, compact, and efficient with respect to tractive power, with respect to wear and tear on the drive unit as well as on the rope, and also efficient with respect to positive and direct driving action on the rope. These objects are further obtained substantially by the use of a pair of rope-winding drums, both of which are actively and directly driven from a sole source of power, with the result that both drums are enabled to assume substantially equal shares of the load at all times.

Other objects have to do with an improved design of the raking means.

Some features of the invention reside in structure of a rake drive mechanism comprising a pair of rope-driving drums having parallel axes, and 30 rotatably mounted in a frame or drive gear casing disposed and extending at one side of the drums. This lateral arrangement of the casing leaves the drums substantially free at the other side, permitting ready application of the rope windings to the drum. When the drum axes are vertical, and the gear casing is located on top, the arrangement readily lends itself for incorporation in the reciprocating sludge-collecting mechanism of a sedimentation tank.

40 The invention possesses other objects and features of advantage, some of which, with the foregoing, will be set forth in the following description. In the following description and in the claims, parts will be identified by specific names 45 for convenience, but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

The novel features considered characteristic of my invention are set forth with particularity in the appended claims. The invention itself, how-

ever, both as to its organization and its method of operation, together with additional objects and advantages thereof, will best be understood from the following description of a specific embodiment when read in connection with the accompanying drawings in which:

Fig. 1 is a plan view of a settling tank equipped with a rope drive unit according to this invention.

Fig. 2 is a longitudinal section of the tank shown in Fig. 1, and shown to be provided with raking mechanism comprising a raking element controlled by a parallel link connection.

Fig. 3 is an enlarged detail plan view of the rope drive unit shown in Figs. 1 and 2.

Fig. 4 is a further enlarged part sectional side view of the unit in Fig. 3.

Fig. 5 is the plan view of a modified construction of a rope drive unit.

Fig. 6 is a relatively enlarged part sectional view of the unit in Fig. 5.

Fig. 7 is a diagrammatic perspective view showing rope windings in crosswise arrangement for driving drums rotating countercurrent to one another (corresponding to the construction shown in Figs. 5 and 6).

Fig. 8 is a plan view of the arrangement in Fig. 7, and showing approximately 270 degrees of the drum engaged by the rope.

Fig. 9 is a diagrammatic perspective view with rope windings in plain spiral arrangement for driving drums with identical sense of rotation (corresponding to the construction shown in Figs. 4 and 5).

Fig. 10 is a plan view of the arrangement in Fig. 9, and showing approximately 180 degrees of the drum engaged by the rope.

A general view of the present rope-driving mechanism as installed in a mechanically cleaned settling tank, is given in Figs. 1 and 2. The tank is shown to be of the longitudinal or rectangular type, having a bottom 10, side walls 11 and 12, an influent end wall 13, and an effluent end wall 14. The influent is indicated by an inlet opening 15, and the effluent by an outlet opening 16. A tentative liquid level in the tank is indicated at 16a. A scum launder is shown at 17. Solids that settle on the bottom in the form of sludge are raked to a sump 18 shown to be located at the inlet end of the tank.

The sludge conveying mechanism has a carriage construction diagrammatically indicated at 19 as having wheels 20, and adapted to travel from end to end of the tank on track rails 21 supported with respect to the side walls of the tank. Depending from the carriage is the rake construction proper in the way of a parallel link construction, namely, the depending link members 22 and 23, and the rake member 24 shown to have a raking blade 25 at one end and spaced therefrom a similar raking blade 26 at the other end. The link connections 22 and 23 permit raising and lowering of the raking member as between sludge-raking position (shown in full lines) and idle position (shown in dot and dash). A weight 26a and auxiliary rope 27 running over pulleys 28 help to raise and lower the rake member 24. The raising and lowering itself of the rake member may be effected by the main drive rope 29 by continued movement of the drive rope, after the carriage has reached an abutment at the end of the tank. A mechanism for this purpose is shown in the patent to Lund No. 2,101,081. That is to say, when the carriage has reached an abutment at the sludge discharge end of the tank, the pull of the drive rope 29 is continued long enough to raise

the raking member a suitable distance from the bottom. By suitable means the rake member is then automatically held locked in this position with respect to the carriage. The rope drive may 5 then be reversed and the carriage returned to the effluent end of the tank, where the carriage is again stopped and the rake member automatically released from its raised position in a similar manner by the action of the rope drive prior to renewed reversal of the carriage.

The main drive rope 29 is actuated by a rope drive mechanism or unit 30 embodying the main features of this invention, and one modification of which is shown in Figs. 3 and 4.

Considering the special adaptation of this construction, for the purposes of the sedimentation tank, it will be noted from the side view in Fig. 4 that the drive unit has a pair of rope-driving drums 31 and 32 disposed side by side, each rotatable about a vertical axis. The drums each are shown to have five grooves 31a and 32a respectively for the rope windings. The one drum 31 is shown to be disposed at a somewhat higher level than the other drum 32, in order to compensate at least partly for the so-called fleet angle, that is, the angle under which the rope from the groove on one drum must otherwise pass to a groove on the other drum.

The drum 31 rotates by way of ball bearings 33 and 34 on a vertical axle 35, the upper end of which is fixed in the hub portion 36 of a casing shell 37 as by means of nut 37a. The drum 31 has fixed to its upper side a gear 38 as indicated by dowel pins 39 or the like. The gear at its lower side is formed with an annular recess 40 to receive therein annular oil-sealing means as will be described.

The other drum 32 is mounted in the casing shell symmetrically to drum 31 and in a manner identical thereto and hence the showing thereof by way of section is not repeated. However, an anchoring nut 41 for the axle of drum 32 will be noted, the corresponding gear for drum 32 being indicated in Fig. 3 by numeral 42. A bridge piece 43 is provided to connect the lower ends of the two drum axles with one another for stability.

Both gears 38 and 42 mesh with a common driving pinion 44 shown to be disposed on the center to center line of the gears 38 and 42. The pinion 44 is at the free end of a vertical drive shaft 44a which may be for instance the outlet shaft of a reduction gear motor indicated at 45 and the housing of which is shown to be bolted as at 46 to the top of the casing shell 37. A bottom portion 47 or plate is fastened to the casing shell 37 as by screws 48. An opening 49 is provided in this bottom portion 47 for the drum 31 and rising from the rim of these openings are annular sealing means 49a lodging in the respective annular recesses 40 of the gears 38 and 42 respectively, and intended to establish oil-sealing contact with the gears. A similar oil-sealing arrangement is provided in conjunction with the other drum 32 and its gear 42, but is not visible in the drawings. The casing has at each end thereof a flange or lug portion 50 and 51 respectively, by means of which it is shown to be bolted to clips or gusset plates 52 and 53 respectively, which in turn are shown to be fastened as by welding to supporting beams 54 and 55, respectively. A guide pulley 56 is fastened to the underside of the casing shell by means of a bracket 57, the pulley to guide the rope onto or off the topmost groove of the drum 32.

With respect to Fig. 3 and Fig. 4, it will be

noted that because of engagement with the common driving pinion 44 the gears 38 and 42 rotate in the same sense, that is to say, either in the direction of the full line arrows 55a or of the dotted line arrows 55b. Consequently, the drive rope is to be applied to these drums in the manner diagrammatically shown in Fig. 9. That is to say, the rope is run around both drums in plain spiral fashion so as to form a series of oval loops or windings (in distinction from the modification in Figs. 5, 6 and 7, where the rope windings intersect forming eight-like shapes). Hence it will be noted that the rope windings according to Fig. 4 and Fig. 9 can be applied or removed without disturbing the bridge piece 43.

Inasmuch as both drums 31 and 32 are driven from a single source, namely pinion 44, it will be noted that frictional contact over an arc of approximately 180° of the occupied grooves on each of the drums 31 and 32 transmits tractive power from the drums to the rope.

The modified unit shown in Figs. 5 and 6 differs from the unit in Figs. 3 and 4, mainly in that it uses a worm instead of a pinion as the common driving element for both rope winding drums, causing the drums to rotate in a sense opposite to one another and necessitating the rope windings to be run crosswise or in figure-eight fashion over the drums.

The Figs. 5 and 6 modification comprises a gear casing 53 comprising a relatively shallow or pan-shaped body portion 59 having a bottom wall 60 and side walls 61, and a top or cover portion 62 bolted to the body portion. Again, there is disposed in the casing in substantially symmetrical arrangement a pair of gears, in this instance worm gears 63 and 64, and there are provided a pair of corresponding rope driving drums 65 and 66. Because of the symmetry only one half of this arrangement need be described. That is to say, the bottom of the gear casing has a downwardly extending hub portion 67 in which rotates a shaft 68 in ball bearings 69 and 70. Fixed upon the upper end 71 of the shaft is the worm gear 63 which is thus wholly enclosed by the gear casing and separated by the casing bottom 60 from the rope winding drum 65 which is fixed to the lower end 72 of the shaft 68.

Both worm gears 63 and 64 are driven by a common worm 73 interposed between them, the worm being suitably journaled in the gear casing. Consequently the drums 65 and 66 run in opposite directions; that is, either in the direction of the full line arrows 73a or of the dotted line arrows 73b.

The worm 73 is shown to be driven by way of reduction gearing 74 from a motor 75 shown to be mounted on the top or cover portion 62 of the gear casing. A drive rope is applied in crosswise fashion to the rope-driving drums, as indicated at 75a in Fig. 5. Each of the drums 65 and 66 has four grooves 65a and 66a, respectively for rope windings (which is one groove less than provided on the drums in Fig. 4).

A clearer, although diagrammatic showing of the crosswise rope windings in this unit is given in Figs. 7 and 8, which are substantially self-explanatory. It will be noted that in this instance the arc of frictional contact between the rope windings and the drums is approximately 270° which compares favorably with the 180° contact in the unit of Fig. 4. Consequently, under normal circumstances there is produced by this unit a traction corresponding to approximately eight times 370°. This may be taken to explain

that the Fig. 6 unit is provided with one less traction groove on each drum than is the unit in Fig. 4 where the frictional contact between the rope and the drums extends over only 180° circumference of each drum. Suitable idler pulley means may be provided for directing the rope as desired to or from the drive unit.

It is a feature common to both forms of the invention, that is to say, according to Fig. 4, as well as according to Fig. 6, that both rope-winding drums are positively and simultaneously driven from a common driving element. In this way it is possible to distribute the tractive power by way of rope friction over both drums. In other words, each groove of each drum takes over its share of the rope friction through which traction is realized. This means in terms of structure that relatively fewer rope windings are needed than are required in cases where one of the drums is an idler and the other drum must transmit all the traction.

This also means that if a pair of rope-winding drums are geared up with one another by way of a common power-driven gear element such as exemplified by the gear 44 in Fig. 4 or the worm 73 in Fig. 6, lost motion cancels out when the mechanism is reversed. In this way both drums are enabled to assume substantially equal shares of the load at all times.

Furthermore, with the construction of a rope-drive mechanism herein shown to be operatively associated with a sediment-collecting mechanism, the rope winds around the drums in horizontal planes, and thereby may fit itself without the need of substantial directional change into the run of the drive rope 29 (see Fig. 1).

The operation of the drive 30 (see Figs. 1 and 2) by means of the drive rope 29 causes the carriage 19 to travel back and forth from end to end of the tank, the forward stroke towards the sludge sump 18 being effective to convey sludge towards and into the sump since the rake member 24 is then in lowered position, the return stroke away from the sump being idle insofar as the rake member 24 is then raised.

Automatic raising or lowering of the rake member 24 in coordination with the carriage movements may be effected in various ways, one method being described in the patent to Lund No. 2,101,081 above mentioned and outlined.

Features of the invention lie in the parallel link construction including the link member 22 and 23, and the rake member 24. In this connection the arrangement of the two raking blades 25 and 26 is of note, for it makes possible the effective cleansing of the entire tank bottom. The blade 26 cleans out the very rear corner of the tank, and conveys the sludge as far as a point designated by an arrow 76, which is spaced a distance d from the edge of the sump 18. Then, on the next forward stroke of the carriage, the blade 25 will pick up what was previously left at point 76 by the blade 26 and push it over the final distance d into the sump 18.

I claim:

1. In a mechanically cleaned settling tank having a rope driven sediment conveying apparatus in which a substantially horizontally disposed drive rope actuates a horizontally reciprocable sediment collecting means, and a self contained power driven rope driving mechanism comprising a horizontally extending frame, gear means mounted in said frame and having a pair of driven gears rotating about vertical parallel axes, a pair

of rope driving drums disposed below said gears and also disposed substantially below said frame so as to be laterally and downwardly substantially free of and unencumbered by interfering adjacent structure, each of which drums is concentrically associated with one of said gears so as to rotate therewith, means for driving said gears, which means comprise a motor mounted above said gears and upon said frame and supported thereby, and also comprising a gear element driven by said motor and in turn having driving engagement simultaneously with both of said pair of driven gears, said drums being adapted to carry rope windings of said drive rope in substantially horizontal planes, which planes are substantially parallel to the horizontal plane of said drive rope system, said drums further being adapted, because of their unencumbered location below said frame, to permit the unobstructed downward displacement of the rope windings from said drums to take place in case of slackening of the rope, and consequently to permit the rope windings to free themselves from engagement with any active part of the drive mechanism, for obviating the entanglement of the rope on the drive mechanism when the latter continues to operate, and means for marginally supporting said frame at points substantially not lower than the uppermost winding on said drums.

2. Mechanism according to claim 1 in which the frame construction comprises a casing for said gear means, which casing has marginal lug portions for support.

3. Mechanism according to claim 1 in which a pair of axles is provided, each of which has its upper end portion non-rotatably and axially non-shiftably mounted in said frame, each axle having rotatably mounted on its intermediate

portion one of said drums together with the associated gear, and having means provided upon and supported by the lower free end portion for retaining said drum and gear in operating position on said axle.

4. Mechanism according to claim 1, in which a pair of axles is provided, each axle having its upper end portion non-rotatably and axially non-shiftably mounted on said frame, each axle having rotatably mounted on its intermediate portion one of said drums together with the associated gear, with the addition of a member supported by and fixedly interconnecting the lower free end portions of said axles, for retaining said drums and gears in their respective operating position upon their axles, said rope windings being disposed in continuous spiral arrangement over both drums, said drive means being effective to rotate both drums in the identical direction.

15 5. Mechanism according to claim 1, in which a pair of shafts is provided, each shaft having its intermediate portion rotatably mounted in said frame, one of said drums being fixedly mounted upon the lower free end portion of each shaft, and one of said gears being fixedly mounted upon the upper free end portion of each shaft.

20 6. Mechanism according to claim 1, in which a pair of shafts is provided, each shaft having its intermediate portion rotatably mounted in said frame, one of said drums being fixedly mounted upon the lower free end portion of each shaft, one of said gears being fixedly mounted upon the upper free end portion of each shaft, said driving means being effective to rotate said gears in opposite directions, and said rope windings being disposed in crosswise fashion about said drums.

CHARLES H. SCOTT.
